(57)

CLAIM

The ornamental design for a bottle, as shown and described.

DESCRIPTION

FIG. 1 is a perspective view of a bottle.

FIG. 2 is side view of the bottle.

FIG. 3 is an opposite side view of the bottle.

FIG. 4 is a top view of the bottle.

FIG. 5 is a bottom view of the bottle; and,

FIG. 6 is a bottom perspective view of the bottle.

The broken lines in the drawings illustrate portions of the bottle and form no part of the claimed design.
